UNITED STATES PATENT OFFICE.

HORACE G. JOHNSON, OF KENOSHA, WISCONSIN, ASSIGNOR OF ONE-HALF TO HENRY S. COOPER, OF KENOSHA, WISCONSIN.

GARMENT.

973,200.

Specification of Letters Patent.

Patented Oct. 18, 1910.

Application filed September 25, 1909. Serial No. 519,569.

To all whom it may concern:

Be it known that I, HORACE G. JOHNSON, a subject of the King of Great Britain, residing at Kenosha, in the county of Kenosha and State of Wisconsin, have invented 5 certain new and useful Improvements in Garments, of which the following is a specification.

This invention relates to that class of 10 underwear known as union suits, and has for its chief object to provide an improved construction of such garments permitting the use of a permanently closed crotch and dispensing with the use of double flaps or a 15 single, wide drop-fall or flap, with their numerous fastenings, heretofore used to cover the posterior opening, while at the same time presenting a posterior opening of ample dimensions for its required purpose covered 20 by a single flap capable of being secured by a single button or other fastening. In other words, my present invention is designed to supply a garment combining in its construction 25 the two most essential requisites for comfort and convenience in garments of this character, namely, a permanently closed crotch, and a posterior opening of ample dimensions and convenient location that will not gap to expose the person and closed by 30 a single flap requiring but a single button or equivalent fastening.

My invention, and its manner of construction and use, will be readily understood when considered in connection with the accompanying drawings illustrating one practical form thereof, and in which—

Figures 1 and 2 are, respectively, front and rear full length elevations of my improved garment, the latter being shown substantially as it would appear on the human figure. Fig. 3 is a detail illustrating the preferred manner of cutting the body and leg portions of the garment to form the posterior opening, preliminary to the application thereto of the flap and gusset-members. Fig. 4 is a view similar to Fig. 3, but showing the flap and gusset members applied, the garment as shown in Figs. 3 and 4 appearing wrong side out. Fig. 5 is a fragmentary plan view in detail of the crotch and adjacent portions of the garment, viewed from the inner side of the latter, as the same would appear were the garment split longitudinally on each side and the front and rear halves of the upper or body portion

spread out in a common plane with the inner sides of the leg portions extending at right angles thereto.

Referring to the drawings, A designates the front, and B the rear or back of the 60 upper or body portion of the garment; and C and D designate the front and rear, respectively, of the leg portions. The front A has a straight opening extending from the neck E to a point slightly above the crotch, 65 the edges adjacent such opening being suitably finished with edging or binding and adapted to be separably united by buttoning over each other, as shown at F, all as usual; said edges being permanently united just 70 above the front end of the crotch as by transverse stitching indicated at G.

The garment herein shown is knit or woven in tubular form from top to bottom, the legs being formed by splitting the tube 75 centrally from the lower end to the crotch, as shown at H in Fig. 3 and then joining the inner edges of the front and rear leg portions by seams I (Fig. 5).

Referring more particularly to Fig. 3, 80 which shows the tubular blank turned inside out, a part of the rear body and leg portions is cut out on the lines a—b, b—c, and c—a; and preferably oblique and transverse cuts a—d and e—f are made in the 85 rear body and leg portions opposite the extremities of the excised portion a, b, c, thereby forming a temporary inner flap member K bounded by the lines d—a, a—b, b—e and e—f. I next form from a separate piece of 90 cloth an external flap L, having the irregular form shown most plainly in Fig. 2, and bounded by the lines g—h, h—i, i—j, j—k, k—l, and l—g. The flap is split vertically 95 for some distance from its lower end forming the edge designated as j—k, and to said edge is stitched the rear edge of a diamond-shaped crotch gusset M, best shown in Fig. 5, the front edge of said gusset being stitched to the front portion just below the 100 lower end of the vertical opening therein, as shown in Fig. 1, and the ends or points of said gusset merging into the leg seams I, as shown in Fig. 5. The edge l—g of the flap L is strongly sewed to the two edges 105 formed by the oblique cut a—d, in the back B, and similarly the edge i—j, of the flap is strongly sewed to the edges formed by the transverse cut e—f, in the diagonally opposed leg portion D; while the longer 110

curved edge $k-l$ is sewed to the edge $c-a$. The edges $g-h$ and $h-i$ of the flap L are free, and the corner or angle formed at the intersection of said edges is adapted to be temporarily secured to the body of the garment to effect the closure of the posterior opening by buttoning, a single button N sufficing.

From the above it will be seen that the described construction provides in the rear of the garment and extending from the line $l-g$ in the back obliquely down to the line $i-j$ in one leg below the crotch a posterior opening defined by the line $l-j$ and guarded by the inner wall member K constituting a part of the body and leg of the garment itself, and the outer wall member comprising the flap L . In the construction of the garment the formation of the cuts $a-d$ and $e-f$ is not indispensable, since the upper and lower ends of the flap L represented by the edges $l-g$ and $i-j$, may be simply sewed to the body and leg portions of the garment; but the cutting of the garment and the uniting of the severed edges to each other and to the edges of the flap makes a much stronger construction, and one less liable to rip or tear. The interposition of the diamond-shaped crotch insert M is not indispensable, since the lower edge of the main flap L might be attached coincidently with the upper ends of the leg seams meeting at the point of the crotch. The use of the crotch insert is, however, preferred, for the reason that it not only affords greater fullness and freedom at the crotch, but also affords greater fullness to the main flap L , effecting a freer gaping of the posterior opening when required.

From the above it will be seen that my invention provides a garment having a permanently closed crotch and a posterior opening extending from a point near the waist-line to a point below the crotch in one leg only. By carrying this opening obliquely from a point substantially in the waist line down to a point on the inner side of the leg below the crotch, I provide a construction affording an opening of ample dimensions and not requiring twisting or lateral displacement of the intermediate portion of the garment when in service. This opening is

covered and fully protected by the single stitched-in flap L , requiring to be buttoned at but a single point to effect a perfect closure. It will be noted that the external flap L completely overlaps the free edge of the underlying section K , providing a seat covering of double thickness to the extent of such overlapping portion; the section K in coöperation with the flap L thus effectually preventing any gaping of the garment or exposure of the person when the main flap is buttoned.

I claim:

1. An undergarment having a permanently closed crotch and a posterior opening extending from a point near the waist-line to a point below the crotch in one leg only, substantially as described. 65

2. An undergarment having a permanently closed crotch and a posterior opening extending from substantially the waist-line at one side of the center to a point in the opposite leg below the crotch, the inner wall 70 of said opening being formed by part of the body and leg portions of the garment and the outer wall being formed by a sewed-in flap having a free portion adapted to button over and close said opening on its outer side, substantially as described. 75

3. An undergarment having the body and leg portions thereof cut to form an oblique posterior opening extending from substantially the waist-line across the seat to a point in the opposite leg below the crotch and an inner flap coextensive with said opening, and an outer flap, said inner and outer flaps and body portion being sewed together at the top of the posterior opening 85 and said inner and outer flaps and leg portion being sewed together at the bottom of said posterior opening and said outer flap having a free portion adapted to button over and close said opening on its outer side, substantially as described. 90

In testimony that I claim the foregoing as my invention, I have hereunto subscribed my name in the presence of two witnesses.

HORACE G. JOHNSON.
